UNITED STATES PATENT OFFICE.

HENRY JOHNSON, OF ARLINGTON, NEW JERSEY.

DESIGN FOR A FOUNDATION FOR SWITCH AND SIGNAL SUPPORTING STANDARDS.

SPECIFICATION forming part of **Design No. 27,869, dated November 16, 1897.**

Application filed July 31, 1897. Serial No. 646,707. Term of patent 14 years.

To all whom it may concern:

Be it known that I, HENRY JOHNSON, a citizen of the United States, residing at Arlington, in the county of Hudson and State of New Jersey, have invented and produced a new and original Design for Foundations for Switch and Signal Supporting Standards, of which the following is a specification, reference being had to the accompanying drawings, forming a part thereof.

Figure 1 is a top plan view of the foundation. Fig. 2 is a side elevation of the same, and Fig. 3 is a transverse vertical section on the line 3 3 of Fig. 2.

The leading features of my design consist in a foundation for switch and signal supporting standards presenting in top plan an oblong, the central portion of which is de-

pressed below the end portions, in side elevation an oblong or rectangle having its upper edge centrally depressed, and in central cross-section a skeleton rectangle, the upper portion of which recedes from the plane of the lower portion.

In the accompanying drawings the end portions are denoted by A A' and a central depressed portion by B.

What I claim is—

The design for a foundation for switch and signal supporting standards, substantially as shown.

HENRY JOHNSON.
